US00D999123S

(12) **United States Design Patent** (10) **Patent No.:** **US D999,123 S**
(45) **Date of Patent:** **** Sep. 19, 2023**

(54) **MOUNTING BRACKET**

- (71) Applicant: **Firestone Industrial Products Company, LLC**, Nashville, TN (US)
- (72) Inventor: **Scott A. Smith**, Brownsburg, IN (US)
- (73) Assignee: **Firestone Industrial Products Company, LLC**, Nashville, TN (US)
- (**) Term: **15 Years**

(21) Appl. No.: **29/859,668**

(22) Filed: **Nov. 11, 2022**

Related U.S. Application Data

- (62) Division of application No. 29/712,053, filed on Nov. 5, 2019, now Pat. No. Des. 969,677.

(57) **CLAIM**

The ornamental design for a mounting bracket, as shown and described.

DESCRIPTION

FIG. 1 is a top perspective view of a mounting bracket illustrating my new design;

FIG. 2 is a bottom perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines in the drawings illustrate portions of the mounting bracket that form no part of the claimed design.

1 Claim, 8 Drawing Sheets
